UNITED STATES PATENT OFFICE.

ROBERT A. HART, OF WEST LIBERTY, PENNSYLVANIA.

PUNCHING-BAG APPARATUS.

1,032,139.

Specification of Letters Patent.

Patented July 9, 1912.

Application filed April 16, 1912. Serial No. 691,124.

To all whom it may concern:

Be it known that I, ROBERT A. HART, a citizen of the United States of America, residing at West Liberty, in the county of Allegheny and State of Pennsylvania, have invented certain new and useful Improvements in Punching-Bag Apparatus, of which the following is a specification, reference being had therein to the accompanying drawing.

This invention relates to a bag punching apparatus, and the primary object of my invention is to provide an apparatus with novel bag supports that permit of a punching bag being placed in various positions on the apparatus, whereby the punching bag can be operated upon from various positions to obtain different kinds of exercise.

Another object of this invention is to provide a punching apparatus that is adjustable, thereby permitting of an overhead punching bag being correctly positioned for exercise.

A further object of this invention is to provide an apparatus of the above type that is inexpensive to manufacture, capable of withstanding the vibrations to which it is subjected, and highly efficient for the purposes for which it is employed.

With the above and other objects in view, the invention resides in the novel construction, combination and arrangement of parts to be hereinafter specifically described and then claimed.

Reference will now be had to the drawings, wherein like numerals denote corresponding parts throughout the several views, in which:—

Figure 1 is a perspective view of a punching bag apparatus, Fig. 2 is an enlarged rear elevation of a frame and strike plate, Fig. 3 is a vertical sectional view of the same, Fig. 4 is a front elevation of a detached strike plate, Fig. 5 is a side elevation of the same as connected to a support, Fig. 6 is a horizontal sectional view of a portion of the apparatus illustrating the adjusting mechanism, Fig. 7 is an enlarged sectional view of a bag hanger, Fig. 8 is an enlarged elevation of a modified form of bag hanger, Fig. 9 is a longitudinal sectional view of the same, and Figs. 10 and 11 are enlarged perspective views of parts of the modified form of bag hanger.

An apparatus in accordance with this invention comprises a platform 1, preferably

rectangular in plan. The platform 1 is supported in an elevated position by legs 2 arranged at the corners of the platform. The legs 2 have the ends thereof provided with sockets 3, said sockets being secured to the platform 1 and to the floor upon which the apparatus is placed. The lugs 2 are provided with T connections 4 and the T's are connected by transverse braces 5 that have cross connections 6 adjacent to the T's 4. The cross connections 6 are vertically aligned with openings 7 in the platform 1, and extending through the connections 6 and the openings 7 are uprights 8. The lower ends of the uprights have elbows 9 connected by transverse braces 10. The braces 10, intermediate the ends thereof, are connected by a longitudinal rod 11 and attached to said rod, intermediate the ends thereof, is a chain 75 or cable 12.

The braces 5 have cross connections 13 intermediate the cross sections 6, and revolvably mounted in the cross connections 13 is a shaft 14 to which the chain 12 is attached 80 and adapted to wind thereon. One end of the shaft 14 has a hand wheel 15 that is provided with a spring pressed pawl 16 engaging a rack 17, carried by the cross connections 13 adjacent to the hand wheel 15. 85 The pawl 16 and the rack 17 are employed for locking the shaft 14 against rotation, after the uprights 8 have been adjusted.

The upper ends of the uprights 8 are provided with elbows 18 and arranged in said 90 elbows are the ends of converging supports 19 that have the inner ends mounted in sockets 20, carried by the periphery of the circular support 21. The support 21 is located centrally above the platform 1 and 95 has a central circular opening 22, said opening having the annular wall thereof provided with a seat 23 for a circular strike plate 24. The strike plate 24 is retained upon the seat 23 by clips 25 pivotally connected to the support 21, as at 26. The clips are diametrically opposed and prevent accidental displacement of the strike plate 24 relatively to its support. The rear side of the strike plate 24 has oppositely disposed 100 handles 27 and oppositely disposed sets of resilient clamping arms 28, that permit of the strike plate being connected to one of the uprights 8, as shown in Fig. 5.

The front side of the strike plate 24 has 110 a central bag hanger, comprising a plurality of converging arms 29 that has the

ends thereof connected by a circular head 30. The head 30 has a central opening 31 for a revoluble sleeve 32, and mounted upon the inner end of the sleeve 32 is a collar 33 that retains the sleeve in engagement with the head 30. The collar 33 is screwed upon the sleeve 32 and is locked thereon by a set screw 34. The outer end of the sleeve 32 has a rounded off flange or bead 35 and said sleeve receives the suspension string or strap 36 of a punching bag 37, said string or strap having the end thereof knotted to retain the same within the sleeve 32.

A set of the uprights 8 have T's 38 provided with arms 39 that are connected to a circular support 40, similar to the support 21. The support 40 is vertically disposed and the lower edge thereof has a socket 41 in which is mounted the upper end of a brace 42, said brace extending through a socket 43 and an opening provided therefor in the platform 1. The brace 42 prevents the support 40 from rotating, and the strike plate 24 can be mounted in the support 41, whereby action can be obtained with the punching bag attached thereto that is altogether different from the exercises performed upon the bag suspended below the support 21.

30 The platform 1 is provided with a post 44 to which the strike plate 24 can be connected for various kinds of exercises, and in order to add rigidity to the upright 8 during exercise, the uprights are braced by 35 tie rods 45 and turn-buckles 46. The tie rods 45 are diagonally disposed and do not interfere with an adjustment of the uprights 8 which as shown in Fig. 1, are in their lowermost position.

40 Fixed upon one of the supports 19 by set screws 47 are collars 48 and movably arranged between said collars is a sleeve 49 that is formed integral with a socket 50 for the string or strap 36 of the punching bag 37. The punching bag 37 can therefore be attached to one of the supports 19, whereby it will swing completely around said supports when it is desired to obtain such exercise that is accomplished by punching the 50 bag.

From the foregoing it will be observed that I have devised an apparatus wherein a stationary platform is provided with an adjustable framework for supporting a 55 punching bag in various positions, whereby it can be easily operated upon. The framework, as illustrated, is made of tubing or gas pipes and provides a strong and durable structure.

60 While in the drawings there are illustrated the preferred embodiments of the invention, it is to be understood that the structural elements are susceptible to such

variations and modifications as fall within the scope of the appended claims.

65

What I claim is:—

1. A punching bag apparatus comprising an elevated platform, a framework adjustably supported by said platform, circular supports carried by said framework, a 70 strike plate detachably connected to one of said supports and capable of being attached to the other of said supports, and a punching bag movably supported by said strike plate.

75

2. A punching bag apparatus embodying an elevated platform, a framework adjustable relatively to said platform, circular supports carried by said framework, a strike plate detachably connected to one of 80 said supports and capable of being attached to the other of said supports, resilient arms carried by the rear face of said strike plate whereby said plate can be attached to said framework, and a punching bag suspended 85 from said strike plate.

85

3. A punching bag apparatus embodying a platform, a framework carried thereby, supports carried by said framework, a strike plate detachably connected to one of 90 said supports and capable of being attached to the other of said supports, a hanger carried by the front side of said strike plate, a punching bag suspended from said hanger, and means carried by the rear side of each 95 support for retaining said strike plate in engagement therewith.

95

4. A punching bag apparatus embodying an elevated platform, a framework movable relatively to said platform, supports 100 carried by said framework, a strike plate detachably connected to one of said supports and capable of being attached to the other of said supports, a punching bag suspended from said strike plate, and means 105 arranged below said platform and including a shaft and a hand wheel for elevating said framework relatively to said platform.

100

5. A punching bag apparatus embodying an elevated platform, a framework adjustably supported thereby, supports carried by 110 said framework, a strike plate detachably connected to one of said supports and capable of being attached to the other of said supports, a hanger carried by said strike 115 plate, a hanger carried by said framework, a punching bag adapted to be suspended from one of said hangers, and means carried by each support for retaining said strike plate in engagement therewith.

115

In testimony whereof I affix my signature in the presence of two witnesses:

ROBERT A. HART.
